UNITED STATES PATENT OFFICE.

EDWIN A. WEBSTER, OF GROVELAND, MASSACHUSETTS, ASSIGNOR TO HAVERHILL CHANNELING MACHINE COMPANY, OF HAVERHILL, MASSACHUSETTS, A CORPORATION OF MAINE.

SOLE-CHANNELING MACHINE.

No. 897,327.

Specification of Letters Patent.

Patented Sept. 1, 1908.

Application filed January 22, 1906. Serial No. 297,094.

To all whom it may concern:

Be it known that I, EDWIN A. WEBSTER, of Groveland, county of Essex, State of Massachusetts, have invented an Improvement 5 in Sole-Channeling Machines, of which the following description, in connection with the accompanying drawings, is a specification, like characters on the drawings representing like parts.

10 This invention relates to certain improvements in that class of machines which are adapted to form a shoulder about or otherwise shape the edge of a sole to be used in a welted or turned shoe and to cut a slit or 15 channel in the sole adjacent said edge. Machines in general use at the present time for this purpose usually comprise two or more fixed knives positioned to make the desired cuts in the sole as the sole is fed past 20 them. In such machines it is customary to employ a pair of feed wheels for drawing the sole against the knives, and, as the bottom of the sole must not be marred in this process, it is customary to employ a smooth faced 25 bottom feed wheel, so that the force necessary to feed the sole must practically all be applied by the upper feed wheel, which is usually provided with projecting teeth which engage the sole in the between-substance, or 30 that portion of the sole between the bottom of the channel and its edge. Generally this between-substance is very narrow, often less than $\frac{1}{8}$ of an inch thick and the result is that the projecting teeth on the upper feed 35 wheel, which are usually nearly as wide as the between-substance is narrow, act to cut the between-substance almost entirely across wherever they enter it, so that the between-substance is thus very materially weakened 40 at many points, and if the needle happens to pass through the between-substance at one of these points the stitch is liable to be pulled out. This weakening of the between-substance is particularly likely to occur 45 about the toe and heel of the sole, as the teeth also tend to tear the between-substance transversely thereof, by reason of the turning of the sole while it is engaged by the teeth, and because of the pulling action more 50 or less transversely of the between-substance.

My invention has for its primary object to produce a sole channeling machine which is adapted to perform its functions without the employment of feeding devices which will in 55 any way injure the between-substance or

cause the same to be weakened during the channel process. I accomplish this object by employing a rotary cutter for forming the shoulder on the edge of the sole and a vibrating or reciprocating knife for cutting the channel, each acting so that they will not cause any resistance to the feeding of the sole by the feed wheel, and so that the strain which is placed upon the sole by the feeding rolls will practically be no more than 60 if said shoulder forming and channeling devices were not present.

For a more complete understanding of my invention reference is made to the accompanying drawing, in which,

Figure 1 is a front elevation of a sole channeling machine made according to my invention. Fig. 2 is an end view thereof. Fig. 3 is the detail view of the cutter operating mechanism. Fig. 4 is a detail sectional view 75 of the knife carrier taken on line 4—4, of Fig. 2. Fig. 5 is a detail sectional view on line 5—5, of Fig. 3. Fig. 6 is a plan view of the machine. Fig. 7 is a rear elevation of the sole engaging mechanism. Figs. 8 and 9 are 80 detail, side and end views of the cutting knife operating mechanism. Fig. 10 is a sectional view on line 10—10, of Fig. 8. Figs. 11 and 12 are detail views showing the knife and cutter in engagement with the work. 85 Fig. 13 is a detail view of the channeling knife. Fig. 14 is a detail sectional view on the line 14—14 of Fig. 9.

In drawings *a* indicates the base of the machine having a frame *a'* thereon in which 90 shafts *b* and *e* are journaled, and a bearing piece *c* is pivoted at *c'* to an upright *a'* on the base, a continuation *b'* of shaft *b* being journaled in said bearing piece and connected thereto by what is commonly known as an 95 "Oldham Joint" *b'*, which permits the two shafts to be moved out of alinement without their being disconnected. An idle pulley *d* is mounted on shaft *e* said pulley constituting one member of a clutch, the other member *d'* 100 being splined on the shaft *e* and being adapted to be moved into engagement with the member *d* by means of a hand lever *d''*, or any other suitable means. Said pulley *d* is driven by a belt *d''* from shaft *x*. The shaft *e* 105 is provided at its end with a smooth faced feed roll *e'*, and a gear *e''* is also mounted on said shaft *e* and is adapted to mesh with a gear *b'* mounted on the shaft *b*, so that the latter is driven from the former. Shaft *b'* is 110

provided at its end with a feed wheel b^4 , the surface of which may be burred or slightly roughened or corrugated to an extent which will not be sufficient to cause injury to the leather or between-substance when the sole 5 is fed between it and the roll e' . A casing f is supported by and pivoted on a pin f' , which is secured in the left hand side of the frame portion a^4 , so that said casing is 10 adapted to swing towards the front on said pivot, as indicated in dotted lines in Fig. 2. Said casing is held in its normal position by a spring fastener f^2 , mounted in the frame, or by any other suitable locking means which is 15 adapted to be readily disengaged. Slidably mounted in said casing f is a holder g which is adapted to move vertically therein, said holder being provided at its lower end with a pair of rearwardly projecting ears g' in which 20 a shaft g^2 is journaled, a pulley g^3 being mounted on said shaft. A cutter shaft g^4 is also journaled in the upper end of the holder g , said cutter shaft having a pulley g^5 mounted thereon and a cutter g^6 , of suitable form, 25 having blades which extend longitudinally of its shaft, is mounted on said shaft at its left hand end, the front ends of the cutter blades being held closely adjacent the adjacent face of the feed roll b^4 . The pulley g^3 is 30 secured to a smaller pulley g^{10} which is driven by a belt x' from pulley x^2 on the driven shaft x , and the cutter shaft g^4 is driven from pulley g^3 by a belt g^7 . A hand screw g^8 is swiveled in the lower end of the 35 holder g and passes through the bottom of the casing f and a spring g^9 is interposed between the bottom of said casing f and the hand wheel g^{10} , which is secured to the lower end of the screw g^8 , so that the holder is normally held by the spring against a stop collar 40 g^{11} on the screw, which is adapted to bear against the bottom of the casing. A sole guard h , of common form, is mounted adjacent the right hand edge of the feed roll e' , 45 said guard being mounted upon a pin h' which passes through the casing, a spring h^2 being adapted to hold the guard in a position adjacent the right hand face of the feed roll b^4 , and any suitable lever mechanism, as indicated at h^3 , may be employed to draw the 50 guard away from said roll b^4 .

The bearing piece c is provided with a dovetail groove or guideway c' , see Figs. 2 and 6, in which a knife support i is slidably mounted. Said support is of angular form having a depending front portion i' in which a pair of vertical ways i^2 are formed, see Fig. 4. A pair of brackets c^2 are formed integral with the bearing piece c and a shaft j is journaled therein, said shaft having a pulley j' thereon which is driven by belt x^3 from shaft x . A bevel gear j^2 is mounted on one end of said shaft j which is adapted to mesh with a bevel gear k , the latter being splined on a shaft k' , which is journaled in two arms i^3

integral with the support i , said arms holding said gear k from vertical movement. A slide m is mounted to move vertically between the ways i^2 of support i , said slide having secured thereto a rod u which extends upward through a yoke i^4 mounted on the support i . A spring w is mounted on rod u and is interposed between the upper end of the slide m and the under side of the yoke i^4 so that nut u' on the upper end of rod u is normally held by spring w against the upper side of the yoke and the slide m is normally held in the position of Fig. 2. A shaft m' is journaled in the lower end of said slide m , said shaft having a beveled gear m^2 at one end 70 which is adapted to mesh with a beveled gear k^2 secured to the lower end of the shaft k' . The shaft k' is also journaled at its lower end, 75 in an arm m^3 which is integral with the slide m .

A guideway block n is provided having a 80 sleeve n' which projects from one side thereof, and is journaled in the lower end of the slide m , the inner face of said sleeve constituting the direct bearing for shaft m' , and said sleeve being held from longitudinal movement in said slide by means of a nut n^2 on the end of said sleeve, see Figs. 2 and 8. The front end of shaft m' is provided with an eccentric pin m^3 , and the guideway block n is provided with T-shaped guide-ways n^3 in 85 which a knife holder o is slidably mounted and supported, as shown in Fig. 8. The knife holder o is provided with a projecting ear o' , see Fig. 10, said ear having a vertical slot o^2 into which the eccentric pin m^3 extends, so that as said shaft m' is rotated said holder will be reciprocated. A knife p is 90 adjustably secured by suitable clamping means in the knife holder o , said knife having a cutting edge at its end which preferably comprises an edge portion p' at the extreme end which is perpendicular to the shank of the knife, and an oblique portion p^2 which is continued for some distance along the side edge of the knife from portion p' , see Fig. 13. The knife block n is adjusted by means of the sleeve n' and nut n^2 into various positions in which the knife p will be oblique to the surface of the feed roll e' , and to the plane of rotation of the cutter g^6 , and the knife p is 95 adapted to be adjusted longitudinally, so that its end edge p' extends to a level between the faces of the feed rolls e' , b^4 , and when in its advanced position, to a point as near to the cutter blades as is the desired thickness of the between - substance. The 100 knife is so positioned that when the holder o is reciprocated the knife p will also be reciprocated longitudinally. The position in which the knife is held is such that its central longitudinal line lies in, or close to the vertical plane which passes through the axes of the feed rolls, that is, the plane in which the axes of the feed rolls lie. The axis of the 105 cutter also lies in this plane, so that both cut- 110

ter and knife engage the work closely adjacent the point at which it is held by the feed rolls.

A vertical rod r is slidably mounted in the frame and said rod r is provided at its upper end with a longitudinal slot r' , the upper portion of said slot extending obliquely of the rod. The support i is provided with a projecting pin i^1 which is normally located in the extreme upper end of the oblique portion of said slot r' , so that when said rod is forced vertically upward, said support i will be moved to the left in its guideways c' , as indicated by the dotted position of Fig. 7. Said guideways c' are preferably parallel to the position in which the knife p , and knife holder guideways n^3 are usually adjusted, so that when the support i is moved to the left it will move the knife longitudinally and draw it up from the face of feed roll e' . A sleeve q is mounted on the rod r and is provided with a projection q' at its upper end, which projection is adapted to engage a pin g^{12} which is secured on the slide g near the upper end thereof. A pin c^3 is rigidly mounted to the front end of the bearing piece c and extends through the slot r' . A spring r^2 is mounted on the lower end of the rod r between the base of the frame a and a hand wheel r^3 on the lower end of the rod, so that said spring normally acts to hold said rod in its lowest position. A pin q^2 is secured in the sleeve q and a pin r^4 is secured in the rod r and forms a support for the lower end of the sleeve q . A foot operated lever s is pivoted in a position to engage the pin q^2 and a foot operated lever t is arranged to engage the pin r^4 . With this arrangement, if it is desired to draw the knife out of the work, the foot lever t is operated so as to lift the rod r , and, as the rod is forced upward; the knife p will be moved upward and to the left, as before described.

The sleeve q will be lifted simultaneously with the rod r when the lever t is operated, and the projection q' of the sleeve is so arranged that when the knife p has been moved outwardly and upwardly as far as possible, so that the pin i^5 will be in the vertical portion of the slot r' , the projection q' will engage the pin g^{12} on the slide g , causing the cutter g^6 to be lifted against the action of the spring g^9 . Immediately after the projection q' engages the pin g^{12} , the pin c^3 on the bearing piece c will be engaged by the rod r at the lower end of the slot r' , so that the whole bearing piece c will be swung upward about the pivot c^6 upon further upward movement of the rod. In this way the feed roll b^4 will be lifted out of engagement with the work which may be held between it and the roll e' . If it is simply desired to lift the cutter g^6 , the other foot lever s will be operated, causing the sleeve q to be moved upwardly, so that its projection q' engages the pin g^{12} . The latter

lever s is ordinarily only used while the sole is being channeled or fitted, it being desirable that the cutter be directly under the control of the operator, while the other lever is ordinarily used only when it is desired to remove or insert the work. The spring g^9 permits the cutter to yield automatically under abnormal conditions, as when the sole is unusually thick or hard.

In operation, when a sole is to be channeled or fitted, the lever t will first be operated, lifting the cutter g^6 , feed roll b^4 , and knife p , so that the sole may be readily inserted between the feed rolls b^4 and e' , with its edge resting against the edge guard h . The cutter g^6 will be rapidly rotated and the knife p will be rapidly reciprocated when the parts are driven and, as the raising and lowering means is entirely independent of the cutter and knife operating means, it will be apparent that the knife and cutter may be raised and lowered while they are being driven. The cutter is adapted and arranged to engage the upper side of the sole adjacent its edge and form the usual shoulder or recess on the edge of the sole. As shown, the diameter of the path in which the cutting edges of the cutter blades move is less than half the diameter of the upper feed roll b^4 . As it is usually desirable to form a vertical or nearly vertical shoulder, at the inner end of the cut made by the cutter blades, as shown in Fig. 12, these blades move below the roll b^4 at their front ends, or ends adjacent said roll, passing up behind it at points a short distance to one side of the vertical plane of the cutter and roll axes. As the leather usually yields somewhat, so that the roll may sink into it to a slight extent, it follows that the sole is pressed down by the roll closely adjacent the point at which the cutter blades emerge therefrom to remove a chip, so that the leather is pressed or held down throughout practically the entire length of the chip, and, as above stated, the ends of the cutter blades move closely adjacent the adjacent or rear side of the roll, so that the leather is also held down closely adjacent the point at which the chip is to be severed at its end. The roll thus coöperates with the cutter in performing at least two important functions:—first in preventing the cutter from lifting up the sole and cutting too deep a shoulder, and second in holding down the leather closely adjacent the point at which each chip is to be severed at its inner end, so that the ends of the cutter blades and the roll have practically a shearing action in cutting away the chips at their inner ends. Without such coöperation most of the chips would be left hanging at the upper edge of the shoulder. The effective coöperation of the roll and cutter which will enable the cutter to cut away the chips at their ends is enhanced by the employment of a feed-roll

having a practically continuous surface, as is the knurled or serrated surface which is employed, as distinguished from a roll having prongs or spurs, which actually penetrate the sole. That is, there is nothing to prevent the roll from pressing down the leather firmly at its edge next the cutter throughout its arc of contact.

The knife p , by being reciprocated longitudinally, will make a chisel like and also a slashing or drawing cut in the sole, and as the sole is fed, will form a slit or channel in the sole in the position ordinarily required. The length of the reciprocations are preferably less than the depth of the channel so that at no time during the cutting operation is the knife totally withdrawn from the channel. This prevents the knife from getting out of the channel and enables a sharp turn to be made in the channel, as in going around a pointed toe, without cutting the channel flap.

In channeling about the toe, and particularly when the toe is sharp, much difficulty has been experienced with prior devices on account of the fact that the edge engaging devices must cut through, or pass over much more space on the sole than the channeling device, so that latter is not cutting at all while the greater part of the edge portion about the toe is being operated upon. Moreover, as is known in the art, with certain prior devices there is liability of the channeling knife passing too close to the edge, so that the "between-substance" is weakened. With my arrangement, however, these difficulties are obviated for the reason that the cutter shapes or shoulders the edge as fast as the sole can be fed to it without a material amount of force being employed to feed the same, the knife acting as a pivot upon which the sole is swung as the cutter passes about the toe. Furthermore, the reciprocating action of the knife forces the sole at all times firmly against the sole guard, and always in the direction of the line which is perpendicular to the edge of the sole at the point at which it is being engaged by the cutter. It will be observed in this connection that the cutter does not oppose this action of the knife in forcing the sole against the guard, so that the possibility that the sole will be channeled too close to the edge is very remote.

The feed rolls b^4 and b^8 are operated at a comparatively slow speed, the speed at which the sole is fed being proportioned to the rapidity of operation of the cutter g^6 and knife b . The extreme end portion p' of the cutting edge of the knife is made vertical to the path of the knife, so that the channel will be cut to a uniform depth, it being so arranged that the sole will not be fed a distance greater than the length of edge portion p' between each complete reciproca-

tion. The greater portion of the cut is made, however, by the oblique and side edge portion p^2 , which gives the stock a drawing cut as it is fed at right angles to the path of the knife against said edge portion p^2 , and as the knife is moved longitudinally, it will be apparent that neither the chisel cut or the drawing cut will materially impede the feeding of the sole, as it would be impeded if the knife were held stationary. The cutter, moreover, is operated so rapidly that it will not materially retard the feeding of the sole, even if it is rotated against the direction in which the sole is fed. The result is that no force is applied to the sole due to the channel and shoulder forming devices, which in more than an inappreciable degree tends to impede the feeding thereof, so that the slight roughness on the feed wheel b^4 is ample to accomplish the rapid feeding of the sole. In this way no injury whatever is done to the between-substance, but the action of the rollers thereon is merely to compress it. The knife may be as narrow as in prior machines, so that a sharp turn in the channel may be made without difficulty.

The means shown for raising the knife obviate the common necessity of starting the channel from the edge of the sole, the knife and cutter being lowered into engagement with the sole after the latter has been placed in position.

To be able to raise either the knife or the cutter partly or wholly out of engagement with the sole is also of importance, for in certain kinds of shoes it is not desirable to have the sole channeled back of the shank, although it is desirable to have the shoulder on the edge formed entirely about the heel, so that the edge may have a uniform shape. To accomplish this result, the lever t may be moved far enough to lift out the knife without raising the cutter, or if it is also desired to raise the cutter to some extent, to decrease the depth of the shoulder, the lever t may be pressed still further. This result may also be accomplished without raising the knife by operating the lever s . It will thus be seen that numerous new results may be accomplished with the above described machine. When it is desired to change or grind the cutter the spring pin f^2 will be drawn out and the holder f will be swung forward on its pivot f' out of proximity to the feed rolls, so that the cutter may be readily removed and replaced.

Having thus described my invention, what I claim as new and desire to secure by Letters Patent is:—

1. In a sole channeling machine, a sole support, a knife-holder-support having guide ways disposed obliquely to said sole support, a knife-holder reciprocally mounted on said guideways, a channeling knife mounted on said holder with its blade extending parallel

to said guideways to points adjacent said sole support and having a cutting edge at its end, and means for reciprocating said knife holder, substantially as described.

5 2. In a sole channeling machine, a sole support, a channeling knife, a support for holding said knife at an angle to the face of said sole support, means for moving said knife with relation to said support to cut the 10 channel, and means for moving said knife support away from said sole support in the direction in which the knife extends to withdraw the latter from the channel, substantially as described.

15 3. In a sole channeling machine, a sole support, a channeling knife having a cutting edge at its end, a knife holder, means for vibrating said holder to move said knife longitudinally in a path at an angle to said support, and means, independent of said vibrating means, for moving said holder away from said support to lift the knife above the upper side of a sole held on said support, substantially as described.

25 4. In a sole channeling machine, a sole support, a knife support, a channeling knife carried by said support having a cutting edge at its end, means for reciprocating said knife longitudinally to cut a channel in a sole 30 held by said sole support, and means, independent of said reciprocating means, for moving said knife support to withdraw the knife from the channel, substantially as described.

35 5. In a sole channeling machine, a sole support, a knife-holder, a channeling knife carried thereby having a cutting edge at its end, means for vibrating said holder to move said knife longitudinally in a path at an angle 40 to said support, and means, independent of said vibrating means, for moving said holder in the direction of said path and away from said support, to lift the knife above the upper side of a sole held on said support, substantially as described.

45 6. In a sole channeling machine, a sole support, a channeling knife having a cutting edge at its end, a knife holder therefor, means for reciprocating said holder to move said 50 knife longitudinally in a path at an angle to the face of said sole support, and means, independent of said reciprocating means, for moving said holder while it is being reciprocated in the direction of said path to withdraw the knife from the sole channel, substantially as described.

55 7. In a sole channeling machine, a sole support, a knife - holder - support, a knife-holder mounted thereon, a channeling knife 60 carried by said holder and having a cutting edge at its end, means for moving said holder on its said support to move said knife longitudinally in a path oblique to said sole support, and means permitting movement of 65 said holder-support in the direction of the

path of said knife and away from said sole support to lift the knife above the sole held thereby, substantially as described.

8. In a sole channeling machine, a sole support, a channeling knife having a cutting edge at its end, a support for said knife having guideways disposed obliquely to the face of said sole support, means for moving said knife support longitudinally on said guideways, and means whereby the inclination of 70 said guideways with relation to said sole support may be varied, substantially as described.

9. In a sole channeling machine, a support, a knife-block carried by and rotatably 80 adjustable in said support, said block having guideways, a knife-holder reciprocally mounted on said guideways, a channeling knife mounted on said holder and having its blade extending parallel to said guideways with a 85 cutting edge at its end, means for reciprocating said holder, a sole support disposed adjacent the end of said blade, and means for locking said knife block in different positions of adjustment to vary the inclination of said 90 ways with relation to said sole support, substantially as described.

10. In a sole channeling machine, a sole support, a driving shaft journaled therein, a knife block carried by said support, and rotatably adjusted about said shaft, said block having guideways, a knife holder reciprocally mounted on said guideways, connections between said shaft and said holder for reciprocating the latter upon rotation of the former, 100 a knife mounted on said holder and extending parallel to said guideways with a cutting edge at its end, a sole support adjacent said cutting edge and means for locking said knife block in different positions of adjustment to vary the inclination of said ways 105 with relation to said sole support, substantially as described.

11. In a sole channeling machine, a sole support, a channel cutting device, a rotary 110 cutter adapted to engage the edge of the sole, means for rotating said cutter, and means for moving said cutter out of engagement with the sole while it is being rotated, substantially as described.

115 12. In a sole channeling machine, a sole support, a feed roll disposed to engage the upper side of a sole held on said support, a rotary, edge-forming cutter disposed to engage the upper side of the sole adjacent the roll, and means for first lifting said cutter and then said roll out of engagement with the sole, substantially as described.

13. In a sole channeling machine, a sole support, a feed roll disposed to engage the 125 upper side of a sole held on said support, a rotary, edge-forming cutter disposed to engage the upper side of the sole adjacent the roll, an operating device and means connected thereto for first lifting said cutter and then 130

said roll out of engagement with the sole, substantially as described.

14. In a sole-channeling machine, a sole support, a feed roll therefor, a channeling knife and a rotary edge-forming cutter disposed above said support in position to engage a sole held thereby at opposite sides of said roll, independently operated means for withdrawing said knife in the direction of its length, and for lifting the cutter, while the roll is in operative position, to permit either the knife or the cutter to operate upon the sole independently of the other, substantially as described.

15. 15. In a sole-channeling machine, a sole support, a roll for feeding the sole over said support, a channel cutting and an edge forming device arranged adjacent thereto, a pair of lifting devices, means operated thereby for lifting said channel cutting and edge forming devices independently of each other and of the roll, and means, operated by one of said lifting-devices, for lifting said roll and said channel-cutting and edge forming devices, substantially as described.

16. In a sole channeling machine, a sole support and feed roll arranged thereabove, a channeling knife, a support for holding said knife obliquely to the face of said support, sole edge forming means, a pair of lifting devices, means, operated by one of said lifting devices, for moving said knife support upwardly in the direction in which the knife extends, to withdraw the latter from the channel, and for thereafter lifting said roll and said edge forming devices from said sole support, and means operated by the other of said lifting devices for lifting said edge forming devices from said support and independently of said knife and said roll, substantially as described.

17. In a sole channeling machine, a sole support, and a sole feeding roll arranged above said support, a rotary cutter, a support in which said cutter is journaled, said roll and cutter being normally held to rotate about axes which lie in the same vertical plane and said cutter being normally held above said sole support and at one side of said roll, and means permitting vertical and horizontal movement of said cutter support, substantially as described.

18. In a sole channeling machine, a sole support, a roll for feeding the sole over said support, a cutter support, a cutter mounted to rotate in said support about an axis approximately in the vertical plane of the axis of said roll, and adapted to engage a sole held on said support, and means permitting horizontal movement of said cutter support, substantially as described.

19. In a sole channeling machine, a sole support, a feed roll disposed to engage the upper side of a sole held on said support, a cutter support, an edge forming cutter

mounted to rotate in said support adjacent the rear side of said roll and disposed to engage the upper side of the sole, and means permitting movement of said cutter support transversely of the cutter's axis to move the cutter from behind the roll, substantially as described.

20. In a sole channeling machine, a sole support, a rotary cutter adapted to engage the edge portion of the sole, a channeling knife having a cutting edge at its end, and means for moving the same longitudinally towards the point at which the cutter engages the sole, and an edge guard disposed to engage the edge of the sole adjacent said point, substantially as described.

21. In a sole channeling machine, a rotary sole-edge engaging cutter, an edge guard, a knife having a cutting edge at its end, and means for moving said knife longitudinally towards the edge guard, said edge guard being arranged and the path of said knife terminating adjacent the same point and at opposite sides of the path of the cutter blades, substantially as described.

22. In a sole channeling machine, a support, a feed roll disposed to press the sole against said support, a transversely rotatable, edge-forming knife having its axis eccentric to the axis of the roll and movable to engage the sole in close proximity to the point of engagement therewith by the roll, substantially as described.

23. In a sole channeling machine, a sole support, a feed roll disposed to press the sole against said support, an edge-forming knife, transversely rotatable about an axis which lies in the plane of the axis of the roll, and between said axis and said support, the path of said knife extending adjacent one side of the roll and beyond the sole-engaging face thereof adjacent said support, substantially as described.

24. In a sole channeling machine, a sole support, a feed roll disposed to press the sole against said support, a transversely rotatable, edge-forming knife having its axis parallel and eccentric to the axis of the roll and movable closely adjacent one side of the roll to pass beyond the periphery thereof adjacent said support, substantially as described.

25. In a sole channeling machine, a support having a sole-receiving face, a feed roll disposed to press the sole against said face, a rotatable edge-forming knife, movable transversely about an axis between said face and the axis of said roll, said axes being approximately parallel and disposed in a plane perpendicular to said face and said knife terminating at its front end closely adjacent the rear side of the roll, and being movable beyond the periphery thereof adjacent said support, substantially as described.

26. In a sole channeling machine, a support having a face to receive the lower side

of the sole, a feed roll disposed to engage the upper side of the sole and press it against said face, an edge-forming knife, transversely rotatable, in a path of less diameter than the 5 diameter of said roll, to engage the upper side of the sole closely adjacent the points at which it is engaged by the roll, substantially as described.

27. In a sole channeling machine, a sole 10 support, a feed roll disposed to press the sole against said support, and a transversely rotatable knife arranged to move transversely of one side of the roll at its periphery with one end in close proximity thereto and adjacent 15 said support, substantially as described.

28. In a sole channeling machine, a sole support, a feed roll having an approximately continuous sole engaging face, disposed to press the sole against said support, and a 20 transversely rotatable knife arranged to move transversely of one side of the roll at its periphery, with one end in close proximity thereto and adjacent said support, substantially as described.

29. In a sole channeling machine, the combination of a sole support, a feed roll disposed to press the sole against said support, said roll having its rear side, adjacent its sole engaging face, in a plane perpendicular to its 30 axis, an edge-forming knife transversely rotatable about an axis parallel and eccentric to the axis of the roll, and in a path extending beyond the periphery of the roll adjacent said support, the front end of said knife being 35 movable in close proximity to said rear side of the roll, substantially as described.

30. In a sole channeling machine, a sole support, a holding device having a sole-engaging face and a side face extending therefrom at an angle, means for pressing said engaging face against a sole to hold the same on said support, and a transversely rotatable, 40 edge-forming knife movable about an axis approximately perpendicular to the plane of said side face in a path extending transversely of said sole engaging face, with one end in close proximity to said side face as its edge, adjacent said support, to permit the holding device to coöperate with the knife 45

in severing the chips, substantially as de- 50 scribed.

31. In a sole channeling machine, a sole support, a feeding device having a sole-engaging face, and a shearing face extending therefrom, at an angle, means for pressing 55 said engaging face against a sole to hold the same on said support, and a transversely rotatable edge-forming blade having a longitudinal cutting edge, and a shearing edge extending therefrom at one end, and movable 60 about an axis approximately perpendicular to the plane of said shearing face, in a path extending transversely of said shearing face with its shearing edge in coöperative relation thereto, substantially as described. 65

32. In a sole channeling machine, a sole support, a roll disposed to press the sole against said support, said roll having a circular shearing face on one side at its edge, a transversely-rotatable, edge-forming knife, 70 movable in a path of less diameter than the roll, eccentric thereto and in position to co-operate at one end with said shearing face, adjacent said support, substantially as described. 75

33. In a sole channeling machine, a sole support, a roll having a peripheral sole-engaging face, with a continuous shearing face at one edge of said peripheral face, means for causing said roll to press the sole against said support, an edge-forming knife having a longitudinal cutting edge and a shearing face at its end extending from said edge, means for moving said knife transversely in a path extending transversely of said shearing face of the roll with its shearing face in coöperative 80 relation thereto, the axes of said roll and said knife being parallel and said shearing face of the roll and said shearing face of the blade being respectively movable in planes perpendicular to said axes, substantially as de- 85 scribed. 90

In testimony whereof, I have signed my name to this specification, in the presence of two subscribing witnesses.

EDWIN A. WEBSTER.
